(No Model.)

G. A. GREEN.

EAVES TROUGH HANGER.

No. 390,122.

Patented Sept. 25, 1888.

A technical line drawing of a mechanical device. At the top, a vertical rectangular rod labeled '12' is shown. Below it, a horizontal metal frame or base is depicted. A curved, ribbed metal component labeled '6' is attached to the right side of the base. On the left side of the base, there is a cylindrical part labeled '8'. A horizontal slot or opening is labeled '10' on the left and '11' on the right. A small circular component, possibly a bearing or washer, is labeled '9' and is positioned between the base and the vertical rod. The drawing uses hatching and cross-hatching to indicate depth and material texture.

UNITED STATES PATENT OFFICE.

GEORGE A. GREEN, OF MAYVILLE, NEW YORK, ASSIGNOR TO HERMAN SIXBEY, OF SAME PLACE.

EAVES-TROUGH HANGER.

SPECIFICATION forming part of Letters Patent No. 390,122, dated September 25, 1888.

Application filed February 25, 1888. Serial No. 265,223. (No model.)

To all whom it may concern:

Be it known that I, GEORGE A. GREEN, a citizen of the United States, residing at Mayville, in the county of Chautauqua and State of New York, have invented certain new and useful Improvements in Eaves-Trough Hangers; and I do hereby declare the following to be a full, clear, and exact description of the invention, such as will enable others skilled in the art to which it appertains to make and use the same.

My improved eaves-trough hanger comprises a band which encircles the eaves-trough, the outer end of that portion of the band running under the trough hooking into the turned-down outer edge of the trough, and the outer end of the upper portion of said band which extends across the trough hooking over the turned-down edge of the trough, a suspending-strap pivotally attached to the top face, and a clamp or brace pivotally attached to the under face of the cross-piece. By thus pivotally attaching the suspending-strap to the cross-piece of the trough-encircling band said hanger or suspending-strap can be attached at any angle, while by passing the band completely around the trough and hooking its ends, respectively, within and around the turned-down outer edge of the trough, and pivotally attaching a clamp or brace-strip to the under face of that portion of the encircling band, so that when in operative position the ends of said brace-piece will press against the inner walls of the trough and clamp them against the encircling-band, the trough is securely and immovably gripped and held in position.

In the accompanying drawings, Figure 1 represents an end elevation of a section of an eaves-trough with my improved hanger in position thereon. Fig. 2 represents a detail view of one of my improved trough-hangers, the trough clamp or brace being shown in dotted lines in unlocked position to permit of the hanger being slipped in position upon the eaves-trough or removed therefrom.

1 represents an eaves-trough of ordinary construction.

My improved trough-hanger comprises three essential parts—viz., a metallic band com-

pletely encircling the trough transversely and 50 adapted, as hereinafter described, to be readily slipped on and off the same, as desired; a clamp or brace pivotally attached to that portion of the metallic band crossing the top of the trough and adapted to be turned on its pivot transversely of said band to permit of said hanger being readily slipped on or off and slid along the trough or turned on its pivot parallel with said band, so as to grip and brace the trough and encircling-band and clamp them 55 rigidly together, and a suspending-strap pivotally connected to the encircling-band. The encircling-band 2 is formed with a curved lower portion, 3, which, when the hanger is in position, encircles or surrounds the outer side 65 walls and bottom of the trough. The end of this curved portion has a curve or hook, 4, formed thereon, which hooks into the downturned outer edge, 5, of the trough.

6 represents a crimp formed in the band, 70 which extends over the inner edge of the trough. From this crimped portion the band extends across the interior of the trough a short distance below its top edges, as shown at 7. The outer end of this cross-piece 7 is 75 hook-shaped, as shown at 8, and hooks over and around the downturned edge of the trough. By thus forming each end of the encircling-band 2 of hook shape, and hooking said ends respectively within and over and 80 around the downturned edge of the trough, and passing the band entirely around the trough, it will be seen that an invincible grip is secured on the trough both at top and bottom, the trough being held from slipping 85 either upwardly or downwardly away from the encircling hanger-band by the oppositely-gripping hooks thereon.

To the under face of the cross piece 7 of the band 2 is connected by a pivot, 9, a brace-piece, 10, having downturned edges 11, which, when said brace is turned into locking position—that is, in alignment with the cross-piece 7—bind against and grip the inner side walls of the trough and press them outwardly 90 against the encircling-band, thereby gripping said trough and band 2 firmly together, and consequently locking the trough securely in 95

position without the possibility of either it or the encircling-band moving or slipping the one away from the other. When the brace 10 is turned on its pivot transversely to the cross-piece 7, as indicated in dotted lines, the trough and encircling-band are unlocked, and the encircling-band can then be readily slipped on or off the trough, or the trough readily slipped away from the encircling-band 2. When the 10 centrally-pivoted brace 10 is turned lengthwise of the trough—that is, transversely to the cross-piece 7—the trough can be readily slipped in position between the upper and lower portions of the encircling-band. Then, 15 upon the trough being placed in position, the brace is turned on its pivot and snapped into place, with its respective ends gripping the inner walls of the trough, thereby immovably holding the trough in place.

20 A perfectly reliable hanger is thus secured which cannot possibly get out of place or fail to hold the trough securely in position.

12 represents the suspending strap. This is formed of an ordinary flat strip of metal having suitable attaching-holes in its length. It has at its lower end a right-angled foot or lug, 13, by means of which it is pivotally connected to the cross piece 7 by the pivot 9, connecting the brace to the cross-piece 7. By thus pivoting the suspending strap 12 it can be turned as desired to secure the connection in any desired position.

What I claim is—

1. An eaves-trough hanger comprising a band encircling the trough and having curved or hook-shaped ends to respectively hook into and around the downturned outer edge of the trough, a suspending-strap secured thereto, and a brace-piece pivotally secured to said en-

circling-band and adapted to engage the respective inner side faces of the trough and grip said band and trough together. 40

2. An eaves-trough hanger comprising a band encircling the trough and having curved or hook-shaped ends to respectively hook into and around the downturned edge of the trough, and a top cross-piece depending within the trough, a suspension-strap pivotally secured to the cross-piece of said encircling-band, and a brace-piece pivotally secured beneath said 50 cross-piece.

3. An eaves-trough hanger comprising a band encircling the trough and having curved ends adapted to engage with the downturned outer edge of the trough, a brace-piece pivotally connected to said encircling-band and having right-angled ends adapted to bind against the inner faces of the trough and press the same against the encircling-band and grip said band and trough together, and a suspending-strap connected to said encircling-band. 55

4. An eaves-trough hanger comprising a band encircling the trough and having curved ends adapted to engage with the downturned outer edge of the trough, as shown, a brace-piece pivotally connected to said encircling-band and having vertically-extending ends adapted to press said trough against the encircling-band and grip said band and trough together, and a suspending-strap pivotally 60 connected to said band, substantially as and for the purpose set forth. 70

In testimony whereof I affix my signature in presence of two witnesses.

GEORGE A. GREEN.
